UNITED STATES PATENT OFFICE.

EDWARD T. CURRAN, OF DETROIT, MICHIGAN.

RADIATOR FOR AIRPLANE ENGINES.

Application filed August 17, 1918. Serial No. 250,277.

To all whom it may concern:

Be it known that I, EDWARD T. CURRAN, citizen of the United States, residing at Detroit, county of Wayne, State of Michigan, have invented a certain new and useful Improvement in Radiators for Airplane Engines, and declare the following to be a full, clear, and exact description of the same, such as will enable others skilled in the art to which it pertains to make and use the same, reference being had to the accompanying drawings, which form a part of this specification.

My invention relates to radiators to be applied to airplane engines. Heretofore the great variation in temperature due to the rapid transfer of an airplane engine while working practically at full capacity from lower to high altitudes and vice versa, renders the maintenance of the proper temperature of the engine very difficult. The radiator I have devised is intended to overcome this difficulty and place the temperature of the engine largely under the control of the aviator. Another object is to reduce the air or head resistance and to produce a more efficient cooling system.

My invention consists in the various novel arrangements and combinations hereinafter described and claimed.

In the drawings:

Figure 1, is a sketch view of an airplane body without wings, as it will appear with my radiator attached.

Figure 2, is an enlarged sectional view of the front end of the airplane of the type in which the propelling fan is of the draft type.

Figure 3, is a further sectional view illustrating the connection.

Figure 4, is a cross section on the line 4-4 of Figure 3.

Figure 5 is a transverse sectional view through the radiator.

Figure 6 is a longitudinal vertical section with parts broken away.

Similar letters refer to similar parts.

In the drawings A, represents the body of an airplane, B, the radiator. The body A carries an engine E, which is diagrammatically shown. This engine is of the usual water cooled type, with water jackets and communications e' to the radiator. As shown in Figure 3, the radiator has a tank C, from which depend water legs D D, which open into a water return flow F,

which in turn communicates with the engine through the pipe e. The water legs D are formed by vertical partitions extending from the upper tank C to the lower tank F. Diagonally cutting the water legs D, are additional water tubes G G, which extend through said partitions and also communicate with the tank C and the water legs D, and open into the water receptacle F. Through the tank C, are vertical openings H H, which perforate the tank and communicate with the spaces between the water legs D, and in the rear of each of these openings H H, are placed rotatable wings J J, which are hinged to the tank C or radiator hood at the rear of each of the openings H H. These wings extend across the top of the radiator and are adapted to be held down as shown in Figure 3, so as to cover the openings H H. In Figure 3, these openings are shown nearly closed by these wings; in Figure 2, they are shown wide open. When the wings are open or partially open, due to the rapid propulsion of the airplane through the air, the air is forced downward through the openings H H and thence through the radiator in direction of the arrows around the diagonal pipes G G and out through openings which perforate the lower water passage F, thereby producing a cooling effect due to the staggering and irregular passage through which it must pass. The circulation of the air is thus transversely through the radiator and also transverse to the direction in which the radiator travels.

In addition thereto I have provided another means of cooling due to a funnel-shaped water jacketed conical opening at K, (Fig. 2) the larger opening being in front of the radiator and the smaller opening K', at the rear of the radiator. L, is the shaft of the propeller passing through a shaft opening M, which opening may also be large enough to permit air to pass through. The separate funnel opening K, might be dispensed with and the shaft opening M be used in lieu thereof as in Fig. 6.

Of course the propeller shaft bearings are of the usual type and need not be described. As heretofore stated, the wings or shutters J J are connected together by a rod N, which is continued to means for control as a notched quadrant and lever at P. Whenever the operator or pilot is placed, it is

supposed this reach rod N and control P are within his reach. At R, is a thermometer or indicator of the usual type connected with the tank C, by which the operator is enabled to observe the temperature of the cooling liquid, in order to guide him in opening or closing the shutters J J, and thereby controlling the temperature to the best advantage.

10 In some machines, it might be well to place the shutters on the under side of the radiator and force the air upward therethrough, instead of downward as shown in the drawing. I do not therefore confine myself to the exact location of the adjustable shutters. The flattened tubes G may be staggered as shown in Figs. 4 and 5.

15 The operation of this device is very readily apprehended from the description. The airplane flying through the air always experiences what might be termed a head wind, otherwise it would not fly at all. The proportions of radiation can be so adjusted, that ordinary cooling might be readily effected through the conical water-jacketed tube K or the shaft opening; but when at high altitude and the air is rare and therefore less effective for cooling and the engine is working at a higher speed, the 20 means shown for controlling the circulation of air can be adjusted to suit conditions and the amount of air thus passing through the radiator, is within the operator's judgment. While I have shown a thermo-siphon circulation, it is obvious that the usual water 25 pumps would be installed to produce a forced circulation, but they would not in any manner add to or modify my invention.

30 What I claim is:

40 1. In a radiator, an upper water space, a lower water space, the outer surfaces thereof being at an angle to each other so that if prolonged they would meet in a frontal direction, water legs connecting the two water 45 spaces, water tubes passing diagonally from one water space to the other and connecting with the water legs, passageways in the water space through which air may pass transversely through the radiator and means 50 for controlling the passage of air therethrough.

55 2. In a radiator an upper water space, a lower water space, the outer surfaces thereof being forwardly convergent at an angle to each other so that if prolonged they would meet in a frontal direction, water legs connecting the upper and lower water spaces, water tubes connecting the water spaces but passing diagonally from one water space to the other and intersecting and communicating with the water legs.

60 3. In a radiator, an upper water space, a lower water space, the outer surfaces thereof being forwardly convergent at an angle

65 to each other so that if prolonged they would meet in a frontal direction, water legs connecting the upper and lower water spaces, water tubes connecting the water spaces but passing diagonally from one water space to the other and intersecting and 70 communicating with water legs, and means whereby air is caused to circulate between the water legs and around the water tubes.

75 4. In a radiator, an upper perforated water space, a lower perforated water space, partitions connecting the water spaces and forming chambers between them, water tubes communicating with and passing diagonally from one water space to the other and through the partition, means for causing air to pass transversely through the water spaces and chambers formed by the partitions and around the water tubes, for 80 the purpose described.

85 5. In a radiator, an upper perforated water space, a lower perforated water space, partitions connecting the water spaces and forming chambers between them, water tubes communicating with and passing diagonally 90 from one water space to the other and through the partitions, means for causing air to pass transversely through the water spaces and chambers formed by the partitions and around the water tubes, and means 95 for controlling the circulation of the air, substantially as described.

100 6. A radiator for vehicles, formed with water passages and air channels, said air channels extending through the radiator in a direction transverse to the direction of travel, and terminating in openings in the forwardly and rearwardly extending walls of the radiator, and shutters hinged to said walls in rear of said openings and extending 105 forwardly and outwardly from the walls.

110 7. A radiator for vehicles, formed with water passages and air channels, said air channels extending through the radiator in a direction transverse to the direction of travel, and terminating in openings in the forwardly and rearwardly extending walls of the radiator, shutters hinged to said walls in rear of said openings and extending forwardly and outwardly from the walls, and a single actuating device connected to operate all of the shutters into position to 115 close said openings.

120 8. A radiator comprising vertical water legs or columns, diagonal spaced water tubes connecting said columns, and means to cause a downward circulation of air through the spaces between the water tubes.

125 In testimony whereof, I sign this specification.

EDWARD T. CURRAN.
